UNITED STATES PATENT OFFICE

GUSTAV E. NORDSTROM, OF GARDNER, MASSACHUSETTS, ASSIGNOR TO AMERICAN FIBRE CORPORATION, OF GARDNER, MASSACHUSETTS, A CORPORATION OF MASSACHUSETTS

REED LOOM

Application filed July 24, 1930. Serial No. 470,365.

This invention relates to looms for weaving fibre reeds or other similar material. Fibre reed is formed from twisted kraft paper and the reed used for weft or filling is supplied to the loom from a reel or drum which is positioned at one side of the loom. This weft reed is drawn from the reel or drum by suitable feeding mechanism and the free end of the reed is projected across the fabric through suitable guideways. One form of feeding mechanism is shown in the prior patent to Nordstrom No. 1,749,840, issued March 11, 1930. After a length of reed is thus inserted, the reed is cut and the inserted piece of reed is beaten into the fabric.

It is the object of my invention to improve the mechanism for guiding and beating up the reed, to the intent that much more rapid operation of the loom may be attained.

A further object of my invention is to provide novel mechanism for moving the beaters in a desired path.

My invention further relates to arrangements and combinations of parts which will be hereinafter described and more particularly pointed out in the appended claims.

A preferred form of the invention is shown in the drawings, in which

Fig. 1 is an end view of the reed guiding devices and the actuating mechanism therefor;

Fig. 2 is a detail front elevation, looking in the direction of the arrow 2 in Fig. 1;

Fig. 3 is a sectional side elevation of the beater operating mechanism, taken along the line 3—3 in Figs. 4 and 5;

Fig. 4 is a plan view of the driving eccentrics and connections, looking in the direction of the arrow 4 in Fig. 3;

Fig. 5 is a front elevation of the beater and its supporting structure, looking in the direction of the arrow 5 in Fig. 3;

Fig. 6 is a sectional side elevation, showing the operative relation of the guiding devices and beater;

Fig. 7 is a detail sectional side elevation, showing the guiding devices in a different relation;

Fig. 8 is a front elevation of the rear or lower guiding device;

Fig. 9 is a rear elevation of the front or upper guiding device;

Fig. 10 is a view similar to Fig. 6 but showing the parts at the beginning of the beat-up motion:

Fig. 11 is a front elevation of the mechanism for cutting the reed;

Fig. 12 is a sectional side elevation of the parts shown in Fig. 11;

Fig. 13 is a detail elevation of the lower end of a knife slide support, and

Fig. 14 is a side elevation of the beater and its supporting frame, and shows the path of movement of the beater in relation to the warp.

Referring to the drawings, I have shown portions of a reed loom including loom sides 10 on which frame members 11 and 12 (Fig. 1) are mounted. Shafts 13 and 14 extend across the loom and are pivotally mounted in the frame members 11 at the opposite sides of the loom. Upper guide members 16 are mounted on the lower shaft 14 and lower guide members 18 are mounted on the upper shaft 13.

An arm 20 (Fig. 1) extends rearward from the upper shaft 13 and is connected by a link 21 to the forwardly extending horizontal arm of a bell crank 22 pivoted at 23 on the loom frame 10. The link 21 is adjustable as to length and also has a bolt and slot connection with the arm 20, so that both the locus and extent of movement of the arm 20 may be easily adjusted and controlled.

A cam roll 24 on a depending arm of the bell crank 22 engages a cam 25 continuously rotated by the cam shaft 26 on which it is mounted. A spring 27 holds the roll 24 in close engagement with the cam 25.

Forwardly extending arms 30 and 31 are secured to the upper and lower shafts 13 and 14. A member 32 (Fig. 2) is pivotally mounted at the outer end of the arm 31, to which it is secured by a pivot stud 33. A member 34 is similarly pivoted at the outer end of the arm 30, to which it is secured by a pivot stud 35.

A rod 36 is adjustable lengthwise in the member 32 and may be secured therein by check nuts 37 and a set screw 38. The upper

90

95

100

portion of the rod 36 extends loosely through an opening in the member 34, and the rod is provided with an enlarged head 39 adapted to engage the upper face of the member 34. I have thus provided a lost motion connection between the arms 30 and 31 so constructed that the amount of lost motion may be readily adjusted.

When the arms 20 and 30 on the upper shaft 13 are rocked by the cam 25, the lower guide members 18 are moved from the stationary guiding position shown in Fig. 6 to the releasing position shown in Fig. 7 before any movement of the shaft 14 and upper guiding members 16 takes place.

The member 34 (Fig. 2) then engages the upper end of the member 32 and the guiding members 16 and 18 are moved to the inoperative position shown in Fig. 10. Suitable springs (not shown) are provided for returning the shafts 13 and 14 and members 16 and 18 to the normal guiding position shown in Figs. 1 and 6.

The upper guiding members 16 (Figs. 7 and 9) are formed as a series of fingers fixed to a plate 40 (Fig. 9) which extends across the loom and is secured to the lower shaft 14, which is preferably of square cross section between its bearings. The guiding members 16 are thickened at their lower ends and are provided with segmental conical guiding openings 41 which are cut away at their lower sides, so that the lower part of each opening is entirely open.

The lower guiding members 18 are similarly formed in the shape of depending fingers secured to a plate 42 extending across the loom and fastened to the side of the upper shaft 13. The fingers 18 are provided with forwardly projecting offset extensions which closely underlie the openings 41 in the lower ends of the fingers 16 when the parts are in the normal position shown in Fig. 6.

With the parts in this position, the reed is projected by suitable feeding mechanism (not shown) through the openings 41 of the upper guiding members 16 and the reed is held in these openings by the forward projections of the lower guiding members 18.

It will be noted that the shafts 13 and 14 are mounted on the fixed members 11 and that they remain in fixed position during the feeding of the reed. This is a substantial advantage, as it permits a fresh reed to be inserted in the guiding members while the lay is beating up the previous reed. This saves a substantial amount of time over the earlier construction of our loom, in which the guiding members were mounted on the lay and it was necessary to bring the lay to rest during each feeding movement.

In Figs. 11 and 13 I have shown mechanism for cutting the reed after it is thus inserted. This mechanism comprises a stationary knife or die plate 50 (Fig. 11) through

which the reed passes from the reel to the guiding members 16 and 18. The reed also passes through an opening in the upper end of a knife slide 51, which is aligned with the opening in the die plate 50 during the feeding of the reed. 70

The knife slide is mounted in suitable guideways 52 (Fig. 12) and is provided with a cam roll 53 for a purpose to be described. At its lower end the slide 51 engages the upper end of a support 54 (Fig. 13), slidably in guideways on the loom frame and engaged by an adjusting screw 55 at its lower end. The slide 54 may thus be vertically adjusted as desired to align the opening in the knife 80 slide 51 with the opening in the die plate 50. The support 54 may then be fixed in position by a binding bolt 56 (Fig. 13) extending through a slot in the support and clamping the support firmly to the loom frame. 85

A coil spring 57 extends between a stud 58 on the knife slide 51 and a stud 59 on the slide support 54. The spring 57 acts to seat the knife slide firmly on the support 54 during the operation of the feeding mechanism. 90

A cam plate or bracket 60 (Figs. 6 and 10) is mounted on the swinging frame of the beater and engages the cam roll 53 as the beater moves rearward, thus lifting the knife slide and severing the inserted reed just prior 95 to release thereof. The raised position of the knife slide is clearly shown in Fig. 10.

The beater of my improved loom is preferably formed by cutting recesses 72 in a beater plate 70 (Fig. 5) thus forming a plurality 100 of beater fingers 71 projecting upwardly from the plate and spaced apart to provide openings for the warp threads. The beater plate 70 is mounted on a lay 73 having downwardly extending supporting arms 74 substantially spaced apart. At their lower ends the arms 74 are mounted on a cross shaft 75 and at their middle portions the arms 74 are connected by a second or upper cross shaft 76 (Fig. 5). 110

At their lower ends the arms 74 are also provided with hub portions 77 which are received in forwardly and downwardly inclined slots or cam openings 78 (Fig. 14) formed in brackets 79 secured to an inner frame 10^a by bolts 80 (Fig. 5) extending through slots in the bracket 79. 115

An eccentric 81 (Figs. 3 and 4) is mounted on a drive shaft 82 and is connected by a link 83 to the lower cross shaft 75. A pair of additional eccentrics 85 are mounted on the shaft 82 in a predetermined angular relation to the eccentric 81, and the eccentrics 85 are connected by links 86 to the end portions of 125 the upper cross shaft 76.

As the eccentric shaft 82 rotates, the lay 73 moves from the full line to the dotted line position shown in Fig. 14 and the upper ends of the fingers 71 describe the closed path in- 130

dicated in broken lines in the upper part of Fig. 14.

The eccentrics are so related that the upper eccentrics 85 swing the lay 73 rearward and downward so that it passes under the guiding members 16 and 18 as indicated in Fig. 6.

The lower eccentric then becomes operative, drawing the lower rock shaft 75 rearward and at the same time causing it to be raised by the action of the cam openings 78 in the brackets 79. The beater fingers are thus raised approximately at their rearward limit of movement and are thereafter moved forward in a position to engage the reed R (Fig. 10) which has been forced downward out of the openings 41 in the upper guiding members 16 by the warp threads W which have been moved downward by the closing of the 20 shed, such movement occurring just after the guiding members have been separated as shown in Fig. 7.

The beater fingers 71 are forced forward in raised position, as indicated in Fig. 14, by the continued action of the eccentrics and at the same time they are gradually lowered by sliding the shaft 75 forward in the cam openings 78.

The action of the lay carrying the beater fingers is thus substantially continuous and without any extended dwell and the motion as produced by the eccentrics 81 and 85 is extremely easy and can be performed at relatively high speed. Furthermore, the feeding 35 of the reed takes place during the beating up of the previously inserted reed, so that a fresh reed is ready to be beaten up as soon as the lay returns to rearward position.

I am thus able to accomplish several very desirable results. In the first place, the reed is fed through guiding members which are stationary during the feeding operation; in the second place, the reed is positively removed from the guiding members by the closing of the warp shed, and in the third place the beating mechanism is operable at relatively high speed and is not required to come to rest during the feeding operation. These and other advantages permit operation 50 of the loom at substantially higher speeds than have been heretofore possible and also reduce the wear on the parts, due to the marked smoothness of the eccentric action.

The improved beater motion shown and described is not claimed specifically in this application, as this mechanism forms the subject-matter of a divisional application Serial No. 507,887, filed by me January 10, 1931.

Having thus described my invention and the advantages thereof, I do not wish to be limited to the details herein disclosed, otherwise than as set forth in the claims, but what I claim is:—

1. In a reed loom, a loom frame, weft reed guiding members mounted on said loom

frame and held stationary during reed guiding operations, and means to separate said members transversely of the weft to release the inserted reed.

2. The combination in a loom as set forth in claim 1, in which said latter means includes a lost motion connection between said members, whereby one of said members is moved only after a predetermined movement of the other member.

3. The combination in a loom as set forth in claim 1, in which cutting devices for the weft reed are provided having weft reed openings normally aligned with the stationary position of the weft reed openings in said weft reed guiding members and in which means is provided to produce relative motion between the parts of said cutting devices before transverse releasing movement of said weft reed guiding devices out of alignment with said cutting devices.

4. In a reed loom, a loom frame, a pair of shafts rotatably mounted therein, a set of weft reed guiding devices mounted on one shaft, a set of cooperating guiding devices mounted on the other shaft, and means to move said shafts to cause said two sets of devices to approach and recede from each other, thereby alternately guiding and releasing the weft reed.

5. The combination in a loom as set forth in claim 4, in which means is provided effective to move one set of said devices to release the weft reed and to thereafter remove both sets of devices from operative position during the beating up of the weft reed.

6. The combination in a loom as set forth in claim 4, in which cam means is provided to cause relative movement of said two sets of devices to release the weft reed, said cam means being thereafter effective to move both sets of devices to inoperative position during the beating up of the weft reed.

7. In a reed loom, weft reed guiding devices, means to insert a weft reed in said devices and to release said weft reed by transverse separation of said devices, and means to beat up a weft reed released from said guiding devices, said inserting and said beating up means simultaneously engaging successive weft reeds.

8. In a reed loom, weft reed guiding devices having a stationary guiding position, a lay, beater fingers on said lay and means to release a weft reed from said guiding devices by relative separation of said devices, transversely of the reed supported therein as the lay approaches back center.

9. In a reed loom, weft reed guiding devices having a stationary guiding position, a lay, beater fingers on said lay, and means to release a weft reed from said guiding devices by relative separation of said devices, transversely of the reed supported therein as the lay approaches back center, said weft reed

being deposited in front of said beater fingers by closing movement of the warp shed.

10. In a reed loom, a set of weft reed guiding fingers having segmental conical guiding openings in their lower end faces and a second set of weft reed guiding devices having offset projections underlying said openings when said parts are in guiding position.

In testimony whereof I have hereunto
10 affixed my signature.

GUSTAV E. NORDSTROM.
